UNITED STATES PATENT OFFICE

WARNER R. BUXTON, OF LONGMEADOW, MASSACHUSETTS

DESIGN FOR A BILL FOLD

Application filed December 24, 1931. Serial No. 42,195. Term of patent 14 years.

To all whom it may concern:

Be it known that I, WARNER R. BUXTON, a citizen of the United States, residing at Longmeadow, in the county of Hampden and State of Massachusetts, have invented a new, original, and ornamental Design for Bill Folds, of which the following is a specification, reference being had to the accompanying drawings, forming part thereof.

Fig. 1 is a front elevational view of a bill fold embodying my new design; and

Fig. 2 is an end elevational view thereof.

In Fig. 1 there are shown two vertically-disposed straps, one near each end of the

bill fold, and each of these straps serves to retain a flap which is folded over from the adjacent end edge of the bill fold. Each such flap has a part which passes beneath the strap and projects therebeyond,—the projecting portion appearing herein as an ellipse.

The design appears wholly on the front side of the bill fold shown in Fig. 1, the reverse side being plain.

I claim:

The ornamental design for a bill fold substantially as shown and described.

WARNER R. BUXTON.
